UNITED STATES PATENT OFFICE.

ALOIS HELFENSTEIN, OF VIENNA, AUSTRIA-HUNGARY.

ELECTRIC FURNACE.

1,082,195.

Specification of Letters Patent. Patented Dec. 23, 1913.

Application filed January 29, 1913. Serial No. 744,921.

To all whom it may concern:

Be it known that I, ALOIS HELFENSTEIN, a citizen of Switzerland, residing at 50 Basstiengasse, Vienna, Austria-Hungary, have 5 invented new and useful Improvements in Electric Furnaces, of which the following is a specification.

This invention relates to closed electric furnaces.

10 It is known to remove the gases of reaction below the receptacle for the charge into laterally arranged gas eliminating chambers in connection with superposed charged receptacles. The drawing off of the gases 15 at the upper end of the charging shaft is also known. (See the furnaces of Gronwall, Lindeblad and Stalhane as also Trunbull in Dr. Paul Askensay's "Die Technische Elektrochmie" vol. 1.)

20 It has been found that for obtaining pure, cooled furnace gases it is particularly advantageous to draw the latter off laterally from the receptacle for the charge surrounding the electrodes, while retaining the mixture as a packing medium for the electrode installation. For this purpose according to 25 the present invention, pipe junctions are let into the sides of the receptacle for the charge, which being distributed around the 30 electrodes, insure the ascending gases being drawn off uniformly.

Compared with known arrangements (for example that of the Austrian Patent 42811) this device has the advantage that the gases 35 must still pass through a part of the mixture in the receptacle for the charge, and thus are purified and further cooled. It can however be also employed in combination with the known arrangement if only a 40 portion of the furnace gases have to be obtained in a cooled and purified form. As compared with the drawing off of the furnace gases in the upper part of the receptacle for the charge the present invention 45 has the considerable advantage, that in the case of freely movable electrodes the mixture itself effects the packing, excluding the entry of vicious air, whereas otherwise, complicated packing constructions must be arranged. Beyond this in the present invention 50 there is the further advantage that the gas discharging device, which in the case of electrodes arranged centrally above the smelting hearth remains freely movable, 55 and the arrangements for supplying the

current is not disturbed and the electrode may readily be exchanged. The junctions may also be formed by inserting uninterrupted partitions in the charging receptacle, which form gas-chambers around the electrodes surrounding the mixture, or the upper part of the receptacle for the charge may consist of a bell with double sides, the inner part of the bell serving for the reception of electrodes and mixture and the 60 outer part respectively the space of the bell situated between the double sides for obtaining the gas.

Different forms of the invention are illustrated in the drawing by way of example. 70

In the form illustrated in vertical transverse section in Figure 1, *a* is the receptacle for the charge placed on the furnace through which the electrode *b* runs—from above. In the receptacle *a* the junctions *c*¹ and *c*² are inserted which serve for conveying the gas out of the same.

In the form of the invention shown in Fig. 2 likewise shown in vertical section, the upper part of the charge receptacle *a* is in the form of a bell with double sides *d*¹ and *d*² by means of which the gas eliminating chamber *e* is formed around the electrode, and from which the gases are carried off by the gas discharge pipes *f*¹ and *f*². 80

In Fig. 3 the invention is illustrated in horizontal section through the three charge receptacles in connection with a tri-phase furnace and in such a manner that the imposed charge receptacles *a*¹ *a*² *a*³ are each 90 divided by the partitions *g*¹ *g*² into an inner charge hopper *h* and gas chambers *i*¹ and *i*² which are connected therewith. The gases are carried off into a common gas pipe *l*¹ and *l*² through the gas pipes *l*¹ and *l*². 95

Having now particularly described and ascertained the nature of my said invention, and in what manner the same is to be performed, I declare that what I claim is:

1. In a closed electric furnace of the character described, the combination with the furnace chamber, of a hopper for the charge, a vertical electrode extending through said hopper, and means within the charge receptacle on top of said chamber for laterally exhausting the gases of combustion and for preheating said charge and cooling said gases of combustion, substantially as described. 100

2. In a closed electric furnace of the char- 110

acter described, the combination with the furnace chamber, of a hopper for the charge, a vertical electrode extending through said hopper, and a double walled bell-shaped body surrounding the electrode and the charge providing an annular space between the double walled bell-shaped body for laterally exhausting the gases of combustion

and for preheating said charge and cooling said gases, substantially as described.

In testimony whereof I affix my signature in presence of two witnesses.

ALOIS HELFENSTEIN.
